UNITED STATES PATENT OFFICE.

WILLIAM A. JAMESON, OF NIAGARA FALLS, NEW YORK.

DESIGN FOR A SPOON, &c.

SPECIFICATION forming part of Design No. 21,555, dated May 24, 1892.

Application filed April 27, 1892. Serial No. 430,916. Term of patent 3½ years.

To all whom it may concern:

Be it known that I, WILLIAM A. JAMESON, a citizen of the United States, residing at Niagara Falls, in the county of Niagara and State 5 of New York, have invented and produced a new and original Design for Spoon and Fork Handles, of which the following is a specification.

This design relates to the ornamentation of 10 spoon and fork handles, and is illustrated in the accompanying drawing, which represents a face view of a spoon embodying my design.

The leading feature of my design consists 15 in the ring or circular field A at the outer end of the handle in connection with the representation of a water-fall b, partly inclosed in the ring. The inner or lower side of the ring A is broken through, as shown at c, and the

part of the water-fall in the foreground is represented as flowing through this gap and 20 down the handle. Bordering both edges of the handle on the inner side of the ring A are curved or rococo ornaments d, and below these ornaments is a ribbon e, which entwines the handle and terminates at the inner end of the 25 handle in a scroll f.

What I claim is—

The design for the handle of a spoon or fork, herein shown and described.

Witness my hand this 21st day of April, 30 1892.

WILLIAM A. JAMESON.
